UNITED STATES PATENT OFFICE.

MILTON C. WHITAKER, OF NEW YORK, N. Y., AND ARTHUR A. BACKHAUS, OF BALTIMORE, MARYLAND, ASSIGNORS TO U. S. INDUSTRIAL ALCOHOL CO., A CORPORATION OF WEST VIRGINIA.

PROCESS OF PRODUCING ETHYLENE.

1,421,640.

Specification of Letters Patent.

Patented July 4, 1922.

Application filed July 11, 1919. Serial No. 310,123.

To all whom it may concern:

Be it known that we, MILTON C. WHITAKER, a citizen of the United States, and a resident of New York city, in the county and State of New York, and ARTHUR A. BACKHAUS, a citizen of the United States, residing at Baltimore and State of Maryland, have invented a certain new and useful Improvement in Processes of Producing Ethylene, of which the following is a specification.

Our invention relates particularly to a method of making ethylene by the use of a catalytic agent.

15 The object of our invention is to provide a process by means of which ethylene may be made catalytically and in an expeditious and economical manner.

Another object of our invention is to provide 20 an advantageous process of making ethylene from ethyl alcohol.

A further object of our invention is to provide a process by means of which ethylene may be produced from ethyl alcohol in such 25 a way as to obtain the maximum yield with the utilization of a minimum amount of heat.

Again another object of our invention is to carry out the process in such a manner as to completely separate the ethylene from 30 the unchanged alcohol.

Still another object is to preheat the alcohol, so as to avoid the presence of liquid alcohol in the chamber where the catalyst is located, in order to avoid loss of the 35 catalyst by the formation of ethyl esters of phosphoric acid.

Further objects of our invention will appear from the detailed description thereof contained hereinafter.

40 While our invention is capable of embodiment in many different forms, for the purpose of illustration we shall describe only one way of carrying out our process herein-after, and while it is capable of being carried 45 out in connection with many different types of apparatus, we have shown only one type of apparatus for use in connection therewith in the accompanying drawing, in which:

50 The figure is a diagrammatic elevation of an apparatus made in accordance with our invention.

In the drawings, we have shown a pipe 1 adapted to conduct hot gases, which may be

heated gases derived from any source, as for 55 example from an oven or furnace, said heated gases being conducted by the pipe 1 to a furnace or reaction chamber 2, having removable top and bottom plates 3 and 4. The furnace 2 is provided with a plurality of 60 vertical tubes 5 supported by two transverse perforated plates 6 and 7, and carrying within the tubes a catalyst adapted to form ethylene from alcohol. The ethylene-forming catalytic material may be comprised of 65 a quantity of comminuted coke or pumice stone carrying phosphoric acid (H_3PO_4), or instead, if desired, carrying finely divided aluminum oxide or kaolin. Preferably the tubes are filled with comminuted coke 70 and the phosphoric acid is then poured into the tubes so as to be absorbed by the comminuted material in the tubes, although it may be made in any other desired manner. The hot gases after passing around the tubes 75 5, leave the furnace 2 by a pipe 8, and thence pass into and downwardly within an alcohol preheater 9 through a plurality of tubes 10 therein, supported by perforated plates 11 and 12, after which the hot gases are conveyed 80 away by a stack 13. The alcohol is fed to the apparatus from an alcohol supply tank 14 by means of a valved trapped pipe 15 to the alcohol preheater 9, within the ascending alcohol is immediately converted 85 into a vapor which passes from the preheater 9 by a pipe 16 to the lower end of the furnace 2. The alcohol vapors are conducted upwardly through the tubes 5 in the furnace 2, where the alcohol is converted to a very 90 large extent into ethylene and water. The vapors of ethylene, alcohol and water leave the top of the furnace 2 by means of a pipe 17, and are conducted to a column heater 18 where they serve to heat a body of water to 95 provide steam for a column 19, the excess water from which is allowed to continually flow away by a pipe 20 connected to the heater, and which leads to a discharge pipe 21 delivering into a funnel 22, whence the 100 water may be conveyed away to any point of disposal. A pipe 23 equalizes the pressures in the pipe 20 and the heater 18. The heater 18 is comprised of a plurality of tubes 23^a supported by perforated plates 23^b and 23^c. The vapors from the heater 18 pass out by a pipe 24, and are conducted to a hot alcohol condenser 25 having a plurality of

tubes 26 supported by perforated plates 27 and 27^a therein, around which the vapors flow. The condenser 25 serves the purpose of removing the major portion of the alcohol and water from the ethylene, so that the alcohol may be returned to the system while warm. From this point, the vapors pass by a pipe 27^b to a cold alcohol condenser 28 having a plurality of tubes 29 supported by 5 perforated plates 29^a and 29^b around which said vapors are caused to flow, so as to remove the residual alcohol and water, and allow the purified ethylene gas to pass out by a pipe 30, whence the ethylene may be 10 collected and utilized in any desired manner. The alcohol and water containing a very little ethylene are returned by pipes 31 and 32 from the condensers 28 and 25 respectively to the column 19. As the vapors pass 15 upwardly through the column 19, the liquid contained in the pans in said column becomes increasingly richer in alcohol, and from the top of said column the alcohol is fed by a pipe 33 to the alcohol preheater 9. The 20 gases and vapors which reach the top of the column 19 pass out of the same by a pipe 34, and thence into a hot condenser 35 having a plurality of tubes 36 supported by perforated plates 37 and 38, from which point the 25 condensed alcohol is conveyed by a pipe 39 to the top of the column 19, so as to provide liquid for sealing the pans in said column. From the hot condenser 35 the gases and 30 vapors passing out of the same are conducted by a pipe 40 to a cold condenser 41 having a plurality of tubes 42 supported by perforated plates 43 and 44, while the residual 35 gases and vapors not condensed therein are conveyed away by a pipe 45 to the pipe 27^b. 40 The condensate from the condenser 41 is conveyed by a pipe 46 to the pipe 39, and thence to the top of the column 19. The condensers 28 and 25, and 41 and 35, may be maintained at the desired temperatures 45 in any suitable manner. For example, the condensers 28 and 25 may be cooled by a current of water passing through pipes 47, 48 and 49, and the condensers 41 and 35 may be cooled by a current of cold water passing 50 through pipes 50, 51 and 52.

In carrying out our invention by the means above described, alcohol is supplied from the tank 14 through the preheater 9 maintained at a temperature of from 300 to 500° C., and 55 to the furnace 2 which is also maintained at a temperature of from 300 to 700° C. where the alcohol vapors formed in the preheater 9 are changed in part to ethylene and water by contact with the phosphoric acid or other 60 catalyst present in the furnace 2. From this point the vapors of ethylene, alcohol and water pass to the column heater 18 where they serve to provide steam for the alcohol concentrating column 19. The ethylene, alcohol and water vapors pass from the col-

umn heater 18 to the hot and cold condensers 25 and 28, whence the condensed alcohol and water containing a little ethylene is conveyed back to the column 19, while the effluent ethylene passes out of the condenser 28 in the form of a gas, and may be collected and used in any desired manner. The concentrated alcohol produced in the column 19 is fed therefrom to the preheater 9. Alcohol to fill the pans of the column 19 is supplied to the column by pipes 39 and 46 leading from the condensers 35 and 41 through which the vapors from the top of the column 19 pass, and from which condensers any quantity of ethylene present is 75 conveyed away to the condenser 28 where any remaining percentage of alcohol and water is removed from the ethylene, and the ethylene becomes added to the main body thereof, so that all of the ethylene is thus 80 recovered at the outlet end of the condenser 28 separated from the alcohol and water.

In this manner the ethylene is recovered after the alcohol and water have been entirely separated therefrom, while at the same 90 time the heat of the various compounds present is utilized throughout the operation of the apparatus, and in such a manner that the apparatus may be operated continuously. Furthermore, the catalyst is utilized to the 95 best advantage as the formation of ethyl compounds thereof is avoided.

While we have described our invention above in detail, we wish it to be understood that many changes may be made therein 100 without departing from the spirit thereof.

We claim—

1. The process of manufacturing ethylene from alcohol comprising preheating the alcohol to a temperature of from 300 to 500° 105 C., and passing the resulting vapors of alcohol through a catalyzer maintained at a similar temperature in order to form ethylene.

2. The process of manufacturing ethylene 110 from alcohol comprising preheating the alcohol to a temperature of from 300 to 500° C., passing the resulting vapors through a catalyzer maintained at a similar temperature in order to form ethylene, condensing 115 out the water and alcohol from the resulting ethylene vapors, conducting the condensed alcohol to a column still to be rectified, and returning the rectified alcohol to the preheater.

3. The process of manufacturing ethylene 120 from alcohol comprising preheating alcohol to a temperature of from 300 to 500° C., and passing the resulting vapors through a phosphoric acid catalyzer maintained at a similar 125 temperature in order to form ethylene.

4. The process of manufacturing ethylene from alcohol comprising preheating alcohol to a temperature of from 300 to 500° C., passing the resulting vapors through a cata- 130

lyzer maintained at a similar temperature in order to form ethylene, condensing out the water and alcohol from the resulting ethylene vapors, conducting the condensed alcohol into a column still to be rectified, removing the rectified alcohol from a point above the point of introduction of the con-

10 densed alcohol, and returning the rectified alcohol to the preheater.

In testimony that we claim the foregoing, 10 we have hereunto set our hands this 3rd day of July, 1919.

MILTON C. WHITAKER.
ARTHUR A. BACKHAUS.
